UNITED STATES PATENT OFFICE.

DANIEL L. CHANDLER, OF AYER, MASSACHUSETTS, ASSIGNOR OF ONE-THIRD TO JOHN H. TRAYNE, OF GROTON, MASSACHUSETTS, AND ONE-THIRD TO EDGAR W. BLAKE, OF PEPPERELL, MASSACHUSETTS.

TUFT-MAKING MACHINE.

1,028,436.

Specification of Letters Patent.

Patented June 4, 1912.

Application filed June 26, 1911. Serial No. 635,258.

To all whom it may concern:

Be it known that I, DANIEL L. CHANDLER, a citizen of the United States, residing at Ayer, in the county of Middlesex and State of Massachusetts, have invented new and useful Improvements in Tuft-Making Machines, of which the following is a specification.

This invention relates to improvements in brush making machinery and particularly to a machine for making tufts for brushes, and has for its object to provide a machine of this class which shall automatically take a bunch of bristles from a mass, double the 15 bristles transversely, insert the tuft thus formed into a suitable holder, and fasten the tuft in the holder.

A further object is to provide means whereby the bristle holder may be made from 20 a continuous piece of tubing.

Another object is to provide means to remove the bur or chamfer the inside of the end of the tube into which the tufts are to be inserted.

Another object is to provide improved 25 means for feeding the bristles from the mass and forming them into loops.

Another object is to provide a novel means for operating upon the bristle holders to 30 secure the bristles therein.

A still further object is to provide means to eject the finished tufts.

To these ends, my invention consists in the 35 novel features of construction and in the combination and arrangement of parts set forth in the following specification and particularly pointed out in the claims.

Referring to the drawings: Figure 1 is a 40 plan of a tuft making machine embodying my invention. Fig. 2 is a front elevation of the machine. Fig. 3 is a side elevation of the machine as viewed from the right hand side of Fig. 2. Fig. 4 is a side elevation of the machine as viewed from the left hand side of Fig. 2. Fig. 5 is an enlarged front elevation of the dies and a portion of their operating mechanism. Fig. 6 is a detail plan section taken on line 6—6 of Fig. 5. Fig. 7 is a sectional view taken on line 7—7 45 of Fig. 1. Fig. 8 is an enlarged sectional view taken on line 8—8 of Fig. 10. Fig. 9

is an enlarged sectional view taken on the irregular line 9—9 of Fig. 1, looking toward the left. Fig. 10 is an enlarged sectional view taken on line 10—10 of Fig. 1, looking 55 toward the right. Fig. 11 is an enlarged detail elevation, partly in section, showing a portion of the tuft feeding and bristle making mechanism shown in Fig. 10, with one plate of the bristle carrier removed. Fig. 60 12 is an enlarged detail plan section taken on line 12—12 of Fig. 2. Fig. 13 is a detail plan section illustrating the action of the needle and bristle carrier inserting the tuft into the end of the tube. Fig. 14 is a detail 65 plan section illustrating the action of the dies for compressing and indenting the tube and the saw which cuts off the tube. Fig. 15 is a detail plan section illustrating the grippers of the ejecting mechanism grasping the bristles of the tuft in readiness to 70 eject the finished tuft after the same has been released by the dies. Fig. 16 is an enlarged elevation of one of the completed tufts. Fig. 17 is an enlarged longitudinal section of a 75 tuft inserted in the chamfered end of the tube before the tube has been compressed. Fig. 18 is a longitudinal section of the tuft and tube, showing the action of one pair of the dies in compressing the tube laterally to 80 form a reduced portion. Fig. 19 is a longitudinal section of the tuft and tube taken on line 19—19 of Fig. 18, showing the action of the second pair of dies in compressing the tube to form the reduced portion and the action of the spurs in forming the indentations which extend into the loop of the tuft. Fig. 20 is a front elevation of all four dies, 85 illustrating their coöperative action upon the tube.

Like numerals refer to like parts throughout the several views of the drawings.

In the drawings, 21 is a main driving shaft journaled in suitable bearings 22 and 23 on a base or frame 24 and having a driving pulley 25. From this shaft most of the mechanisms of the machine receive their power.

Bristle feeding and tuft forming mechanism. (See Figs. 1, 4, 8, 10 and 11, particularly Figs. 8, 10 and 11.)—A hopper 26 for the bristles consists of two walls 27 and

28 provided, respectively, with grooves 29 and 30 constituting ways to receive a weight 31 arranged to slide vertically therein. This weight which serves to crowd the 5 bristles downwardly in the hopper may be provided with one or more supplementary weights 32 mounted upon an upwardly extending rod 33. The hopper has a back wall 34 on one side and the mass of bristles is 10 inserted in the hopper, as shown in Fig. 8, with the ends of the bristles against the wall 34, as illustrated in Fig. 8. The weight 31 is then put in place so that its lower end rests upon the central portion of the 15 uppermost bristles, as shown in Fig. 8, it being understood, however, that when the hopper is loaded it will preferably be loaded with a greater mass of bristles than is shown in the drawings. A fourth wall 35 extending 20 part way up the side of the hopper serves to confine the ends of the bristles at that side. This wall is preferably removable in order to facilitate the introduction of the mass of bristles and to that end is 25 mounted to slide vertically and is supported upon two screws 36 and 37. The hopper 26 which is otherwise open at the bottom is provided with two downwardly curved depending guides 38 and 39 so 30 shaped as to guide the bristles to the lowermost point thereof where they are to be engaged by the feeding devices. Preferably, the bottom of the weight 31 is provided with a V-shaped notch 40 so formed 35 as to facilitate the crowding of the bristles toward the lowermost point of the guides 38 and 39.

The lowermost bristles of the mass in the hopper rest upon a bristle carrier 41 in 40 the manner shown in Figs. 8, 10 and 11. This bristle carrier consists of two plates 42 and 43 separated by a space in which is located a plate 44 carrying at its upper portion a very thin plate or needle 45 provided at its forward end with a notch or recess 46 designed to engage the bristles as they are crowded down into a recess or throat 47 provided in the upper side of the plates 42 and 43 of the bristle carrier 41. 45 Preferably, the size of this recess or throat is varied by means of two adjustable plates 48 and 49, see Figs. 10 and 11, secured to the opposite sides of the bristle carrier 41. The bristle carrier 41 is provided with a longitudinal 50 passage 50, preferably cylindrical in form, communicating with the recess or throat 47 and also communicating with a slot 51 in which the needle 45 reciprocates, said needle also extending up into 55 said cylindrical passage, as clearly shown in Fig. 8.

The plates 42 and 43 which constitute the bristle carrier 41 are secured to a slide 52 mounted to slide on a suitable guide 53 60 provided on a bracket 54 mounted on the

base of the machine. This slide is reciprocated at the proper times in the operation of the machine by a cam 55, see Figs. 1 and 10; secured to the shaft 21 and having a groove 56 in which is located a cam roll 70 57 journaled on the slide 52. The plate 44 is secured to a slide 58 mounted to slide in suitable ways provided in the slide 52 and the slide 58 is reciprocated at the proper times in the operation of the machine by 75 means of a cam 59 secured to the shaft 21 and having a groove 60 in which is located a cam roll 61 journaled on the slide 58.

In the operation of the bristle feeding and tuft forming mechanism, the needle 45 80 is first advanced past the recess or throat 47 and in so doing said needle engages a number of bristles located in said recess and in advancing beyond said recess, said needle doubles the bristles transversely 85 thereof and forces them into the cylindrical passage 50, thus forming a tuft having a loop engaged by the needle. The tuft thus formed is carried forward to a point adjacent to the end or nose of the bristle carrier 90 41, said bristle carrier is then advanced to a point adjacent to the holder into which the bristles are to be inserted, as will appear more fully hereinafter, and then the needle 45 is advanced within the bristle carrier 95 to carry the tuft out of the bristle carrier into the bristle holder. Preferably, the slide 52 has secured thereto a plate 62 which is adapted to pass between the guides 38 and 39 and crowd the mass of bristles in 100 the bottom of the hopper toward the throat or recess 47.

Tube feeding mechanism. (See Figs. 1, 2, 3, 7 and 12.)—A suitable metallic tube 63 passes between a pair of feed rolls 64 105 and 65 secured to shafts 66 and 67, respectively, the latter shaft being journaled in suitable bearings 68 and 69 provided on a slide 70 mounted to slide transversely of the longitudinal dimension of the tube 63 110 in ways 71 provided on a bracket 72 secured to the base 24. The shaft 66 is journaled in bearings 73 and 74 mounted to slide vertically in ways 75 and 76 provided on the slide 70. Suitable compression springs 77 and 78 provided with adjusting screws 79 and 80, respectively, urge the bearings 73 and 74 downwardly, thus causing the feed roll 64 to press the tube 63 against the feed roll 65 and assuring sufficient frictional engagement so that the tube may be properly fed when the shafts 66 and 67 are rotated. The shafts 66 and 67 are geared together by gears 81 and 82 secured to said shafts, respectively, and meshing with each other, 120 thus causing said shafts to be rotated in unison and the feed rolls 64 and 65 to be positively driven at the same speed.

At the proper times in the operation of the machine, the feed rolls 64 and 65 are ro- 130

tated to the proper extent to feed the tube longitudinally by suitable mechanism. Preferably, this mechanism comprises a ratchet 83 having a hub 84 journaled in a 5 suitable bearing provided in a bracket 85 and held against longitudinal movement therein by a collar 86 secured to said hub. The ratchet 83 is provided at its opposite side with a hub 87 upon which a pawl carrying lever 88 is mounted to rock and held against longitudinal movement by a collar 89 secured to said hub.

Mounted upon the pawl carrier 88 is a feed pawl 90 engaging the teeth of the 15 ratchet 83, see particularly Fig. 3, arranged to drive said ratchet in one direction, while a stop pawl 91 (see Fig. 3) pivoted upon the bracket 85 and engaging said ratchet prevents reverse rotation thereof. The pawl 20 carrier 88 is rocked at the proper times in the operation of the machine by a slide 92 (see Fig. 3) connected at its forward end to said pawl carrier by a pivot 93 (see Fig. 3) and having its rear end mounted to slide in 25 a suitable guide 94 in which it is capable of moving not only longitudinally, but vertically as well so as to permit of a certain amount of rocking movement due to the path of the pivot 93. The slide is reciprocated by a cam 95 secured to the shaft 21 and having a groove 96 in which is located a cam roll 97 journaled on said slide. Preferably, 30 the slide 92 is formed, for the purposes of adjustment, in two parts secured to each 35 other by bolts 98 and 99, see Figs. 1 and 3.

That part of the tube feeding mechanism which has already been described imparts an intermittent longitudinal feeding movement to the tube 63 at the proper times in 40 the operation of the machine. At certain times in the operation of the machine, the tube is moved from right to left, Fig. 1, in order to present the end of the tube first to the action of a bur-removing or chamfering 45 means and then to the action of dies for compressing the walls of the tube, as will appear hereinafter. In order that the tube may be properly guided and held at that end which is to be operated upon by these instruments, there is provided a guide 50 100, see particularly Fig. 1, secured to the slide 70. It will be evident that since the slide 70 is to be moved to carry the feed rolls 64 and 65 to and fro from right to 55 left and vice versa, there must be provided a sliding connection between the shaft 67 and the ratchet 83 and to this end said ratchet is provided with a key or feather 101 arranged to slide in a key-way 102 provided in said shaft. The slide 70 is reciprocated by a suitable mechanism preferably comprising a link 103 pivotally connected at one end to said slide and at its other end to a rocker arm 104, see particularly Fig. 2, 60 secured to a rock shaft 105. This rock

shaft, which is journaled in suitable bearings 106 on the base 24, is rocked at the proper times in the operation of the machine by a cam 107 secured to the shaft 21 having a groove 108 in which is located a cam roll 109 journaled on an arm 110 secured to said rock shaft. By means of the tube feeding mechanism hereinbefore described, the tube is fed longitudinally and presented to the action of the different instrumentalities 75 which operate upon the same, as will be more fully described hereinafter.

Tube chamfering or bur-removing mechanism. (See Figs. 1, 3 and 12).—In order that the bur may be removed from the 80 previously cut end of the tube 63, there is provided a suitable rotating chamfering tool 111, see particularly Fig. 12, suitably shaped to bevel or chamfer the inside of the end of the tube and to also slightly chamfer the outside of said end, as will be evident from an inspection of Fig. 12. This tool is mounted in a suitable holder or chuck consisting of a shaft 112 having a longitudinally split and tapered portion 113 onto 85 which is screwed a tapered collar 114 by means of which said tapered portion may be contracted to grip and hold the shank of the chamfering tool 111. The shaft 112 is journaled in suitable bearings 115 and 116, 90 see particularly Fig. 3, on a slide 117 mounted to slide on suitable ways 118 provided on the bracket 54, see Fig. 8.

At the proper time in the operation of the machine, the slide 117 is carried forward and back to carry the chamfering tool toward and away from the end of the tube by means of a cam 119 secured to the shaft 21 and having a groove 120 in which is located a cam roll 121 journaled on said slide. 100 The shaft 112 is rotated by means of a belt 122 passing around a pulley 123 secured to said shaft. When the tube 63 is presented at the proper time to be chamfered, the rotating chamfering tool is advanced to the 105 position shown in Fig. 12, the end of the tube is thus chamfered, and the chamfering tool recedes, thus leaving the tube free to be carried toward the left, Fig. 12.

Tube compressing and indenting mechanism. (See Figs. 1, 2, 5, 6, 10, 13, 14, 15, 18, 19 and 20).—After the bur has been removed from the end of the tube by chamfering the same, as hereinbefore described, the tube is carried from the position shown in Fig. 1 toward the left, a longitudinal feeding movement is imparted thereto to bring the same into the position shown in Fig. 13, and the tuft is then inserted into the chamfered end of the tube in the manner shown 120 in Fig. 13 by advancing the needle 45 into the position shown into the tube. After this has taken place, the end of the tube containing the tuft of bristles is compressed 125 and indented by the following mechanism. 130

Referring now particularly to Fig. 5, it will be observed that grouped about the end of the tube 63 there is a plurality of dies for accomplishing the compressing and indenting of the tube, these dies being preferably four in number arranged in pairs, one pair consisting of the members 124 and 125 and the other pair consisting of the members 126 and 127, all of which are mounted to slide radially in a circular die holder 128 and are given a longitudinal sliding movement therein by means of a ring 129 swiveled upon said die holder. This ring carries a plurality of arms 130, 131, 132 and 133 pivoted thereto and pivoted to the outer ends of the dies 124, 125, 126 and 127, respectively, as shown in Figs. 5 and 6. As this ring is rocked to and fro on the stationary die holder 128 by a mechanism which will be described hereinafter, the swinging arms just described act to impart to their respective dies a simultaneous movement toward the tube and away from the tube. Preferably, the extremities of the dies where they engage the tube are substantially cylindrical in form and also helical or inclined at an angle to the axis of the tube 63. The purpose of this helical form of the dies is to prevent the walls of the tube from being crippled to too great an extent by the throwing out of ribs between the dies. It will be seen that the size of these ribs would be increased if the die faces were parallel to the axis of the tube instead of being inclined, as just described, or, in other words, the tube would be crippled to such an extent as to impair its power to hold the bristles. Preferably, the die members 126 and 127 are provided, respectively, with spurs 134 and 135 which indent the tube and form indentations 136 and 137 extending into the loop of the tuft in the manner illustrated in Figs. 18 and 19, particularly Fig. 19, thus locking the tuft within the tube. It is also highly desirable that the holder shall be compressed around that portion which is located between the indentations 136 and 137 and the end of the tube from which the bristles project and to this end the die members 124, 125, 126 and 127 are provided, respectively, with more or less abrupt shoulders 138, 139, 140 and 141, as best illustrated in Figs. 18 and 19, these shouldered portions of the dies serving to form a reduced portion or neck 142 firmly gripping the bristles adjacent to that end of the holder or tube from which they project. Thus the entire operation of compressing the holder or tube and indenting the same is simultaneously accomplished by the simultaneous action of all four of the die members. The die actuating ring 129 is rocked to and fro by any suitable means and for this purpose I preferably provide said ring with a depending arm 143 connected by a link 144 to

a rocker arm 145 secured to a rock shaft 146 journaled in bearings 147 on the base 24. A rocking motion is imparted to the rock shaft 146 by means of a cam 148 secured to the shaft 21 and having a groove 149 in which 70 is located a cam roll 150 journaled on an arm 151 secured to said rock shaft.

Tube cutting off mechanism. (See Figs. 1, 2, 4, 12, 13, 14 and 15.)—After the bristles have been inserted in the end of the tube and the end of the tube has been compressed and indented, as just described, that portion of the tube which contains the bristles is cut off of the remainder of the tube by suitable means preferably consisting of a circular saw 152 which, as shown in Figs. 12 to 15, inclusive, is placed adjacent to the front face of the dies and the die holder. This saw is secured to a shaft 153 journaled in a suitable bearing provided in a rocker arm 154 secured to a rock shaft 155 mounted in suitable bearings 156 on the base 24. The shaft 153 has secured thereto a spur gear 157 meshing into a gear 158 secured to a shaft 159 also journaled in the rocker arm 154 and having secured thereto a pulley 160 driven by a belt 161 from overhead. The saw is carried to and fro across the path of the tube 63 at the proper times in the operation of the machine by a cam 162 secured to the shaft 21 and having a groove 163 in which is located a cam roll 164 journaled on an arm 165 secured to the rock shaft 155.

an arm 103 secured to the rock shaft 100. By the mechanism just described, the tube is severed thus leaving a portion thereof 100 forming a holder in which the bristles are firmly secured, the remainder of the tube being returned to its initial position to be operated upon by the bur-removing or chamfering mechanism. 105

Tuft ejecting mechanism. (See Figs. 1, 4, 8, 9 and 10.)—Referring particularly to Fig. 9, 166 and 167 are grippers or jaws constituting pincers, said jaws being connected to each other by a pivot 168. The jaw 167 is provided with a rearwardly extending arm 169, while the jaw 166 is prolonged rearwardly to form a slide 170 mounted in guides 171 and 172. This slide is carried forward and backward at the proper times in the operation of the machine by suitable mechanism as, for example, a link 173 pivotally connected at one end to said slide and at its other end to a lever 174, see Fig. 1, provided with an angular slot 175 in which is located a pin 176 carried by the slide 52. The lever 174 is fulcrumed upon a standard 177, see Fig. 10. The gripper 167 is rocked upon its pivot 168 at the proper times in the operation of the machine by a device which is commonly known as a four-motion feed and which comprises a plate 178 provided with a lateral recess 179 in which is located a stationary guide block 180 and a pivoted switch block 181, said 110 115 120 125 130

recess being provided adjacent to the under side of said switch block with an upwardly inclined surface 182. The arm 169 is provided with a laterally projecting pin 183 extending into the lateral recess 179 and said arm is equipped with a suitable spring 184 whose tendency is to keep the jaws 166 and 167 closed. When, however, the slide 170 is retracted from the position shown in Fig. 9, the pin 183 travels along the bottom of the recess 179 up the inclined surface 182, thereby displacing the switch plate 181 and arriving at the extreme right hand end of said recess. The switch plate 181 may then drop by gravity or it may be provided with a spring 185 connected to an arm 186 secured to a rock shaft 187 to which the switch plate 181 is also secured. This spring assures the return of the switch plate to the position shown in Fig. 9, after the pin 183 has passed therebeyond. When this has occurred, it is evident that the jaws 166 and 167 will be opened, since by this action the arm 169 has been rocked upwardly from the position shown in Fig. 9. When this has taken place, the next forward motion of the slide 170 acts to carry the pins 183 along the top of the switch plate 181 and the stationary block 180 and said pin is returned by the spring 184 to the position shown in Fig. 9. While the compressing, indenting and sawing of the tube is taking place, the grippers 166 and 167 are advanced by the mechanism just described into the position shown in Fig. 9 and grip the bristles, as shown in said figure and as shown in Figs. 12 and 15. As soon as the dies open and release the bristle holder, the grippers recede from the position shown in Fig. 9 and open, thus dropping the tuft onto a chute 188, see Figs. 1 and 4. Sometimes the bristles have a tendency to stick to the grippers and would not be released with certainty and, accordingly, I provide a plate 189, see Figs. 1 and 9, secured to the wall 28 of the hopper 26 and extending to a point adjacent to the top of the gripper 166, as shown in Fig. 9. When the grippers recede from the position shown in Fig. 9, some of the upwardly projecting bristles of the tuft engage the front face of the plate 189 and discharge the tuft from the grippers into the chute 188.

The general operation of the machine hereinbefore described is as follows: The tube is first presented to the action of the bur-removing or chamfering mechanism, the inside of the end of the tube is chamfered, the tube is then carried into a position between the dies and thus presented to the action of the tuft inserting mechanism. A set of bristles is taken from the mass in the hopper and bent transversely to form a tuft having a loop by the co-operative action of the needle and bristle carrier. The bristle carrier is then advanced to a point adjacent

to the end of the tube, as shown in Figs. 13 and 14, the loop of the tuft is inserted in the chamfered end of the tube, the tube is then compressed and indented, and that portion of the tube which contains the tuft is cut off from the remainder of the tube, thus leaving the bristle holder held by the dies. The grippers of the ejecting mechanism having gripped the bristles of the tuft, the dies open and release the finished tuft and the same is then removed from the dies and dropped onto the chute. The parts then return to their initial positions ready for another operation.

Having thus described my invention, what I claim and desire by Letters Patent to secure is:

1. A tuft making machine having, in combination, means to remove the bur from the end of a tube, means for placing a bunch of bristles in said tube, and means to compress said tube against said bristles to bind the same therein.

2. A tuft making machine having, in combination, means for chamfering the inside of the end of a tube, means for inserting a bunch of bristles in said tube, and means to compress said tube against said bristles to bind the same therein.

3. A tuft making machine having, in combination, means for chamfering the inside of the end of a tube, means for inserting a bunch of bristles into said tube, and means to present said tube first to the action of said chamfering means and then to said bristle inserting means.

4. A tuft making machine having, in combination, means for chamfering the inside of the end of a tube, means for inserting a bunch of bristles into said tube, means for compressing said tube against said bristles to hold the same therein, and means to present said tube first to the action of said chamfering means and then to said bristle inserting and tube compressing means.

5. A tuft making machine having, in combination, means for inserting a bunch of bristles into the end of a tube, and means for cutting off of said tube the portion containing said bristles.

6. A tuft making machine having, in combination, means for inserting a bunch of bristles into the end of a tube, means for fastening said bristles in said tube, and means for cutting off of said tube the portion containing said bristles.

7. A tuft making machine having, in combination, means for inserting a bunch of bristles into the end of a tube, means for compressing said tube to bind said bristles therein, and means for cutting off of said tube the portion containing said bristles.

8. A tuft making machine having, in combination, means for chamfering the inside of the end of a tube, means for inserting a

bunch of bristles into said end of said tube, means for compressing said tube to bind said bristles therein, means for presenting said tube first to the action of said chamfering means and then to said bristle inserting and tube compressing means, and means for cutting off of said tube the portion containing said bristles.

9. A tuft making machine having, in combination, means for imparting a longitudinal feeding movement to a tube, means to guide said tube, means to chamfer the inside of the end of said tube, means to insert a set of bristles into the chamfered end of said tube, and means to cut off of said tube the portion containing said bristles.

10. A tuft making machine having, in combination, means for imparting a longitudinal feeding movement to a tube, means to guide said tube, means to chamfer the inside of the end of said tube, means to insert a set of bristles into the chamfered end of said tube, means to move said guiding and feeding means to present said tube first to the action of said chamfering means and then to said bristle inserting means, and means to cut off of said tube the portion containing said bristles.

11. A tuft making machine having, in combination, a plurality of coöperating dies, means to impart a longitudinal feeding movement to a tube to carry the same between said dies, means to insert a bunch of bristles in said tube, and means to relatively actuate said dies to compress said tube against said bristles therein.

12. A tuft making machine having, in combination, a plurality of coöperating dies, means to impart a longitudinal feeding movement to a tube to carry the same between said dies, means to insert a bunch of bristles in said tube, means to relatively actuate said dies to compress said tube against said bristles therein, and means to cut off of said tube the portion containing said bristles.

13. A tuft making machine having, in combination, a plurality of coöperating dies, means to impart a longitudinal feeding movement to a tube to carry the same between said dies, means to insert a bunch of bristles in said tube, means to relatively actuate said dies to compress said tube against said bristles therein, means to cut off of said tube the portion containing said bristles, and means to eject the finished tuft from said dies.

14. A tuft making machine having, in combination, a plurality of coöperating dies, means to impart a longitudinal feeding movement to a tube to carry the same between said dies, means to insert a bunch of bristles in said tube, means to relatively actuate said dies to compress said tube against said bristles therein, means to cut off of said

tube the portion containing said bristles, and means to grasp said bristles while said tube is held by said dies and remove the finished tuft after being released by said dies.

15. A tuft making machine having, in combination, a plurality of coöperating dies, means to chamfer the inside of the end of a tube, instrumentalities to impart a transverse movement to said tube to carry the same from said chamfering means to a position adjacent to said dies and to impart a longitudinal feeding movement to said tube to carry the chamfered end between said dies, means to insert a set of bristles into said chamfered end, means to relatively actuate said dies to compress said tube against said bristles, and means to cut off of said tube the portion containing said bristles.

16. A tuft making machine having, in combination, a plurality of coöperating dies, means to chamfer the inside of the end of a tube, instrumentalities to impart a transverse movement to said tube to carry the same from said chamfering means to a position adjacent to said dies and to impart a longitudinal feeding movement to said tube to carry the chamfered end between said dies, means to insert a set of bristles into said chamfered end, means to relatively actuate said dies to compress said tube against said bristles, means to cut off of said tube the portion containing said bristles, and means to eject the finished tuft from said dies.

17. A tuft making machine having, in combination, a plurality of coöperating dies, means to impart a longitudinal feeding movement to a tube to carry the same between said dies, means to insert a bunch of bristles in said tube, means to relatively actuate said dies to compress said tube against said bristles therein, a saw disposed in a plane intersecting the path of longitudinal feeding of said tube, and means to carry said saw across said path to cut off of said tube the portion containing said bristles.

18. A tuft making machine having, in combination, means to support a bristle-holder, a hopper for the bristles, a bristle-carrier, a needle to engage a set of the bristles and carry the same from said hopper into said carrier, means to advance said bristle-carrier to a point adjacent to said bristle-holder, and means to advance said needle to carry said set of bristles from said bristle-carrier into said bristle-holder.

19. A tuft making machine having, in combination, means to support a bristle holder, a hopper for the bristles, a bristle-carrier having a passage therein, a needle to engage a set of bristles intermediate their ends and carry the same into said passage thereby doubling said bristles, means to advance said bristle-carrier to a point adjacent to

to said bristle-holder, and means to advance said needle to carry said set of bristles from said bristle-carrier into said bristle-holder.

20. A tuft making machine having, in combination, means to support a bristle holder, a hopper for the bristles, a bristle-carrier having a passage therein, a needle, and means to move said needle relatively to said bristle-carrier thereby to double said set of bristles into said passage to form a tuft and insert said tuft into said bristle holder.

21. A tuft making machine having, in combination, a hopper having at its bottom an outlet for bristles, a bristle-carrier having a throat located beneath said outlet to receive bristles therefrom and having a passage communicating with said throat, a needle, and means to actuate said needle to carry a set of bristles lodged in said throat into said passage thereby doubling the same to form a tuft.

22. A tuft making machine having, in combination, a hopper having adjacent to the bottom an outlet for the bristles, a bristle-carrier located beneath said hopper, said carrier being provided in its upper side with a recess to receive bristles from said hopper and being provided with a passage communicating with said recess, a needle, and means to carry a set of bristles lodged in said recess into said passage thereby doubling the same to form a tuft.

23. A tuft making machine having, in combination, a hopper having adjacent to the bottom an outlet for the bristles, means to crowd the mass of bristles in said hopper downwardly toward said outlet, a bristle-carrier located beneath said hopper, said carrier being provided in its upper side with a recess to receive bristles from said hopper and being provided with a passage communicating with said recess, a needle, and

means to carry a set of bristles lodged in said recess into said passage thereby doubling the same to form a tuft.

24. A tuft making machine having, in combination, a hopper having adjacent to the bottom an outlet for the bristles, a bristle-carrier located beneath said hopper, said carrier being provided in its upper side with a recess to receive bristles from said hopper and being provided with a passage communicating with said recess, means to vary the size of said recess, a needle, and means to carry a set of bristles lodged in said recess into said passage thereby doubling the same to form a tuft.

25. A tuft making machine having, in combination, a hopper for the bristles, a bristle-carrier arranged at the bottom of said hopper to support the mass of bristles therein, said bristle-carrier being provided with a passage, and a needle mounted to reciprocate in said passage thereby to carry a set of bristles from said mass into said passage.

26. A tuft making machine having, in combination, a hopper for the bristles, a bristle-carrier arranged at the bottom of said hopper to support the mass of bristles therein, said bristle-carrier being provided with a passage and with a recess in its upper side communicating with said passage, a needle mounted to reciprocate in said passage and across said recess, and means to actuate said needle to engage a set of bristles in said recess, bend the same transversely and into said passage to form a tuft.

In testimony whereof I have hereunto set my hand in presence of two subscribing witnesses.

DANIEL L. CHANDLER.
